UNITED STATES PATENT OFFICE

170,923

RADIO RECEIVER

Dorman D. Israel, New Rochelle, Arthur C. Germer, North Merrick, and Kenneth E. E. James, Laurelton, N. Y., assignors to Emerson Radio and Phonograph Corporation, New York, N. Y., a corporation of New York

Application July 16, 1953, Serial No. 25,996

Term of patent 14 years

(Cl. D56—4)

To all whom it may concern:

Be it known that we, Dorman D. Israel and Arthur C. Germer, both citizens of the United States, and Kenneth E. E. James, a citizen of Great Britain, residing, respectively, at New Rochelle, county of Westchester, State of New York; N. Merrick, county of Nassau, State of New York; and Laurelton, county of Queens, State of New York, have invented a new, original, and ornamental Design for a Radio Receiver, of which the following is a specification, reference being had to the accompanying drawing, forming part thereof, wherein:

Figure 1 is a perspective view of a radio receiver, showing our new design; and

Figure 2 is a top plan view.

We claim:

The ornamental design for a radio receiver, as shown.

DORMAN D. ISRAEL.
ARTHUR C. GERMER.
KENNETH E. E. JAMES.
